UNITED STATES PATENT OFFICE

173,331

DISPLAY RACK FOR GREETING CARDS AND ALLIED MERCHANDISE

Frederick W. Vaughan, Islip, N. Y., assignor to
Munson, Inc., Babylon, N. Y.

Application March 29, 1954, Serial No. 29,726

Term of patent 14 years

(Cl. D80—10)

To all whom it may concern:

Be it known that I, Frederick W. Vaughan, a citizen of the United States of America, residing in Islip, county of Suffolk, and State of New York, have invented a new, original, and ornamental Design for a Display Rack for Greeting Cards and Allied Merchandise, of which the following is a specification, reference being had to the accompanying drawing, forming part thereof, wherein,

Figure 1 is a front elevational view of a display rack for greeting cards and allied merchandise, showing my new design.

Figure 2 is a top plan view thereof, drawn to a smaller scale.

The rear and side views of the display rack are

identical in appearance to the side shown in Figure 1.

I claim:

The ornamental design for a display rack for greeting cards and allied merchandise, substantially as shown and described.
